UNITED STATES PATENT OFFICE.

LAWRENCE J. DESENBERG, OF LOS ANGELES, CALIFORNIA.

GAME.

1,164,791.

Specification of Letters Patent. Patented Dec. 21, 1915.

Application filed May 18, 1915. Serial No. 28,838.

To all whom it may concern:

Be it known that I, LAWRENCE J. DESENBERG, a citizen of the United States, residing at Los Angeles, in the county of Los Angeles and State of California, have invented a new and useful Game, of which the following is a specification.

This invention aims to provide an interesting and attractive game for adults as well as children and one of the objects is to provide a game which offers an element of chance, requires skill in the playing thereof and which includes apparatus with which many kinds of games, like those played on a pool table may be played.

Another object is to provide inexpensive game apparatus which is constructed so that it may be held in the hands of the player and easily played, the principal game pieces being balls, which are caused to gravitate to different points upon a game board by tilting the apparatus.

The invention consists in certain novel features of construction and combinations, and arrangement of parts as will be more fully hereinafter described and pointed out in the claims.

Referring to the drawings: Figure 1 is a top plan view of my improved game board; Fig. 2 is a top plan view showing some of the game members in scoring position; and Fig. 3 is a cross sectional view taken on line x^3-x^4 , of Fig. 1.

Referring to the drawings, 1 designates a substantially rectangular and flat game board which is constructed of wood, cardboard, metal or any other suitable material and is preferably of a size to permit the player to hold it in the hands. At the four corners of the board pockets 2, 3, 4 and 5 are formed, each pocket being identical as to construction and size and opening upon the board. Side pockets 6 and 7 of the same size and shape as are the end pockets are formed at diametrically opposite points centrally of the longitudinal edges of the board, making six pockets in all.

The board is provided with side walls 8 and 9 and end walls 10 and 11 joined with the side walls. These walls 8, 9, 10 and 11 are arranged to form the walls of the pockets and at points where the pockets are formed the game board 1 is provided with outward extensions 12, each of which is substantially semi-circular and forms the bottom wall of a pocket. It will thus be

seen that the bottom walls of the pockets are level with the surface of the game board 1. The side and end walls are curved outwardly and secured to the peripheries of the extensions or projections 12 so as to provide walls for the pockets and are extended toward one another at the mouths of the pockets to provide retaining flanges 13 which flanges restrict the mouths of the pockets and act to retain the game pieces in the pocket to a certain extent. Marked upon the game board near one of the end walls, for example, the end wall 10, are rings 14 which indicate points at which a plurality of balls 15 are to be positioned in order to play the game. The rings are arranged in V formation and are six in number, preferably, thus requiring six balls 15. Each of the balls is numbered from one to six, inclusive. Upon the center of the board 1 is marked a ring 16. This ring indicates the point for standing a game piece 17. The game piece 17 is preferably in the form of a tenpin or bottle and is to be knocked down by the balls 15.

The game is played as follows: The game piece 17 and the balls 15 are placed in position at the points indicated by the markings 14 and 16 and the board is held in the hands of the player and tilted to cause the balls to gravitate into the pockets. The player should try to direct one of the balls into engagement with the game piece so as to knock the game piece over. Only one ball should be contained in a pocket, and should the player in tilting the board cause one of the balls to roll out of the pocket, or the game piece to fall, the turn is lost and the next player places the balls and game piece in starting position again. The retaining flanges 13 act to a certain extent to prevent the balls from rolling out of the pockets too readily while the player is tilting the board. The score is determined by the balls remaining in the pocket when the player loses his turn, the numbers on the balls being added to determine the points scored. The knocking down of the bottle with a ball preferably counts 5. If the player pockets all six balls, he continues to play after again setting the balls in starting position.

The game is preferably thirty-one points and if a player scores more than thirty-one points his entire score is lost and he loses his turn. The game piece must be set upon the

ring 16 in the center of the table each time it is knocked down. It will be seen that the object of this game is to roll as many balls as possible into the pockets, one ball in each 5 pocket, and to cause one of the balls to knock the game piece down.

While I have described only one game which may be played with my game apparatus, it is to be understood that the 10 players may make their own rules and other games similar to those which may be played upon a pool table may be played as readily as the one described in the foregoing.

In practice I have found that the form of 15 my invention illustrated in the drawings and referred to in the above description as the preferred embodiment is the most efficient and practical, yet realizing that the conditions concurrent with the adoption of my 20 device will necessarily vary, I desire to emphasize the fact that various minor changes in construction, proportion and arrangement of parts may be resorted to when required without sacrificing any of the 25 advantages of my invention as set forth in the appended claims.

I claim:

1. A game comprising a flat game board having a plurality of ball-receiving pockets 30 about the edges thereof, a plurality of balls to be gravitated into the pockets by tilting the board, and a game piece mounted in upright position upon the board and adapted to be knocked down by the balls.

35 2. A game comprising a flat substantially rectangular game board having a plurality of outward extensions at the corners thereof and at points between certain corners, side walls carried on the edges of the game board 40 and extending around the extensions to provide walls for said extensions and form pockets, a game piece adapted to be mounted in upright position upon said board, and a plurality of balls to be gravitated into engagement with the game piece and into the 45 pockets, by tilting the board.

3. A game comprising a flat substantially

rectangular game board having a plurality of outward extensions at the corners thereof and at points between certain corners, 50 side walls carried on the edges of the game board and extending around the extensions to provide walls for said extensions and form pockets, a game piece adapted to be mounted in upright position upon said board, a plurality of balls to be gravitated into engagement with the game piece and 55 into the pockets by tilting the board, and retaining flanges carried by the side walls and extending toward one another at points 60 where said extensions are joined to the board, to obstruct the openings of the pockets and retain the balls in the pockets.

4. A game comprising a flat game board having a plurality of pockets about the 65 edges thereof, said pockets having their floors level with the game board, a game piece adapted to be mounted in upright position upon the board, and a plurality of balls mounted upon the board and adapted to 70 be gravitated into the pockets and into engagement with the game piece by tilting the board.

5. A game comprising a flat game board having a plurality of pockets about the 75 edges thereof, said pockets having their floors level with the game board, a game piece adapted to be mounted in upright position upon the board, a plurality of balls mounted upon the board and adapted to be 80 gravitated into the pockets and into engagement with the game piece by tilting the board, retaining flanges extending from opposite sides of the pockets at the mouths thereof and restricting the openings at the 85 mouths of the pockets, and side walls for said game board.

In testimony whereof, I have hereunto set my hand at Los Angeles, California, this 11th day of May, 1915.

LAWRENCE J. DESENBERG.
